SUCTION CLEANER

Uncas A. Whitaker, Canton, Ohio, assignor to
The Hoover Company, North Canton, Ohio, a
corporation of Ohio

Application December 30, 1933, Serial No. 704,636

12 Claims. (Cl. 15—9)

The present invention relates to suction cleaners in general and particularly to improvements in a suction cleaner provided with dusting tools. More specifically the invention comprises a cleaner in which the conversion of the cleaner from a unit adapted for on-the-floor cleaning to a unit adapted for off-the-floor cleaning automatically results in the production of a higher suction by the cleaner for use in the dusting tools.

It is an object of the present invention to provide a new and improved suction cleaner. It is another object of the invention to provide a suction cleaner of the convertible type adapted for both on-the-floor cleaning and off-the-floor cleaning, the conversion of the cleaner from one unit to the other resulting in a modification of its suction-producing power. A still further object is the provision of a suction cleaner in which permanent valves are incorporated for the purpose of determining the functional operation of the machine, means being combined with the function-altering means which change the speed of cleaner motor rotation to effect higher suctions when the machine is used as an off-the-floor unit. Still another object is the provision of a suction cleaner in which the conversion of the machine from an on-the-floor cleaner to an off-the-floor cleaner results in higher motor speed and in the production of greater suction. These and other more specific objects will appear upon reading the following specification and claims and upon considering in connection therewith the attached drawings to which they relate.

Referring now to the drawings in which the same reference characters refer to the same parts throughout:

Figure 1 is a side elevation of a modern suction cleaner equipped with the present invention, certain parts being broken away;

Figure 2 is a partial section through the cleaner shown in Figure 1, being taken upon the line 2—2 of Figure 1;

Figure 3 is a section through a portion of the cleaner, being taken upon the line 3—3 of Figure 2;

Figure 4 is a diagrammatic showing of the electrical circuit of the cleaner;

Figure 5 is a section upon the line 5—5 of Figure 2;

Figure 6 is a section upon the line 6—6 of Figure 5;

Figure 7 is a partial section through a cleaner embodying a second preferred embodiment of the invention, being taken upon the line 7—7 of Figure 8;

Figure 8 is a partial section through the bottom of the second modification of the invention.

The modern suction cleaner is a unit adapted for use in cleaning surface coverings or articles positioned above that covering. In operation as an on-the-floor unit when cleaning coverings reliance is placed upon an agitating member, in combination with the moving air, to remove the embedded foreign matter in the covering. When used in off-the-floor cleaning the aforementioned agitating member is unused and the suction created by the machine is made available at a point spaced from the cleaner proper by means of a dusting tool which is connected to the unit, and in particular to the suction-creating means thereof. When used in on-the-floor cleaning it is not desirable that the suction in the cleaner nozzle exceed a definite limit because of the presence of the surface covering agitator. In the use of the cleaner in off-the-floor cleaning, however, no limitations need be placed upon the degree of suction and a higher suction is desirable. In a suction cleaner constructed in accordance with the present invention, the conversion of the machine from an on-the-floor cleaner to an off-the-floor cleaner automatically results in greater suction for use in the dusting tools than was available for use in the cleaner nozzle in on-the-floor cleaning.

Referring again to the drawings, and Figures 1 to 6 inclusive in particular, a preferred embodiment of the invention is disclosed. A modern cleaner is disclosed which is seen to comprise a nozzle 1, a fan chamber 2, and exhaust outlet 3, and a motor casing 4 which is positioned immediately above the fan chamber. The nozzle 1 is interiorly connected to the inlet 5 of the fan chamber 2 by means of an air passageway 6. The cleaning air drawn between the surface-contacting nozzle lips 7 and 8 traverses this passageway 6 in response to the suction created by the rotating fan 9 carried by the extended motor shaft 10 within chamber 2. The air after entering the fan chamber 2 is exhausted through the chamber exhaust outlet into the connected dust bag 11 of the usual type.

Within the nozzle 1 is the rotatably mounted agitator 12 comprising an elongated body carrying surface-contacting rigid beater elements and flexible brush elements. Agitator 12 is rotated by means of a belt 13 which extends through the air passageway 6 and connects to a driving pulley 14 carried at the extreme lower end of the motor shaft 10. In the cleaning operation the agitator 12 cooperates with the air stream entering the

nozzle 1 by dislodging the embedded foreign matter in the surface covering which is then carried away by the air and deposited in the dust bag 11. As in the usual suction cleaner front and rear supporting wheels 15, 15 and 16, 16 are provided which support the nozzle 1 above the surface covering undergoing cleaning and permit of the easy movement of the cleaner over the covering. The usual pivoted handle 17 is provided which is connected to the body of the machine and provides means by which the operator can propel the machine. The incoming power leads 18, 18 to the cleaner motor extend down the handle 17 and to the motor of the machine in the usual manner, one of the leads first passing through a manually operable handle switch 19 of the usual type, shown diagrammatically in Figure 4. The parts described comprise the entire cleaner construction necessary for on-the-floor cleaning. They comprise the usual and well known cleaner and no invention is claimed in their general arrangement or specific construction except as hereinafter disclosed.

In order to convert the machine to an off-the-floor cleaner the air passageway 6 adjacent the eye 5 of the fan chamber is provided with an inlet 20 from which extends a transverse conduit 21. Conduit 21 is provided with a spring-pressed detent 22 which is adapted to cooperate with a groove 23 on the inner end of a dusting tool hose 24 to lock and retain removably the hose in place in the conduit. The dusting tool hose 24 is of a common and well known type including a flexible conduit which is adapted to be connected to a usual nozzle at its outer end. The inlet 20, is normally closed in the operation of the machine in on-the-floor cleaning by a pivoted valve 25 which is normally held in inlet-closing position by a coil spring 26. The valve 25 is opened upon the insertion of the dusting tool hose 24 by means of a plunger 27 connected to the valve which is contacted by the end of the hose as it is moved inwardly to its seat. The valve is shown in the open position in dotted lines in Figure 2, where it is held as long as the dusting tool hose is seated in the conduit 21.

It is also necessary, however, to close the nozzle 1 from the inlet 5 of the fan chamber in order to direct the entire suction created by the fan to the inlet 20 and so to the dusting tool. To accomplish this function a second pivoted valve 28 is provided which extends across the air passageway 6, being pivoted at the top thereof and being provided with a cutaway section 29 of minimum size to permit the passage of the driving belt 13. Valve 28 is directly connected to valve 25 by means of a link 30 and a rigid arm 31 on the valve 25. With the valve 25 held in the closed position by the spring 26 the arm 31 is pivoted to the position shown in full lines in Figure 2 and valve 28 is held upwardly against the top of the air passageway 6 in its open position by the link 30. With the valve 25 moved to the open position, shown in dotted lines in Figure 2, the arm 31 is moved from the valve 28, see dotted line showing in Figure 2, and that member is pivoted to its closed position, as shown in dotted lines in Figure 1. The two valves are fixedly connected and when one valve is open the other valve is shut, and vice versa.

The movement of the valves results not only in the connection of a new source of air flow to the suction-creating fan and fan chamber, but also results in greater speed of rotation of the 75 motor and consequently of the fan 9 carried

thereby. To accomplish this result the pivotal shaft 32 of the valve 28 is extended outwardly through the side wall of the air passageway 6 and is provided with a portion at right angles to the axis of the shaft. A plunger member 33 of insulating material is carried by an insulating housing 35 on the cleaner casing and extends into contact with this right angle end of the pivotal shaft 32. Plunger 33 is capable of limited sliding movement permitted by spaced shoulders 34, 34 formed in its insulated housing 35. Within the housing 35 are positioned two contacts 36 and 37, the first being a stationary contact and the second a movable contact of spring-like material which normally moves to an open position and is contacted by the inner end of the slide 33. Contact 37 urges the plunger 33 outwardly and toward the angularly disposed end of shaft 32. Contacts 36 and 37 are directly connected by leads 38, 38 in series with a resistance R and around a portion of a field winding of the cleaner motor, as clearly shown diagrammatically in Figure 4. The relationship between the contacts 36, 37, the plunger 33, and the right angle end of the shaft 32, is such that with the valve 28 in the open position, that is the position in which it would be with the cleaner functioning as an on-the-floor unit, the end of shaft 32 does not contact the plunger 33 and the plunger is in its outermost position and the two contacts 36 and 37 are separated. With the valve 28 pivoted to its passageway-closing position, its position when the machine is used in off-the-floor cleaning, the end of the shaft 32 has contacted the plunger 33, and has urged and moved it inwardly forcing the contact 37 against contact 36.

As is clearly seen in Figure 4 the resistance R is in parallel with a portion of the motor field winding and upon its inclusion in the motor circuit the armature of the motor rotates at higher speed. The desirable result of rotating the fan 9 at higher speed is thus seen to be accomplished.

Referring now to Figures 7 and 8 a second preferred embodiment of the invention is disclosed. In this embodiment the general construction of the cleaner is exactly that described in connection with the first embodiment. In this construction, however, the valves which control the direction of air flow in the cleaner are not automatically operated by the dusting tool hose upon its connection or upon its removal. The dusting tool hose 24 again seats within the conduit 21 and is retained therein as before by the cooperation of the spring-pressed detent 22 and the shouldered groove 23. The plunger 27 of the first embodiment, together with the coil spring 26, have been omitted. In their place a manually operable slide member 40 has been provided which is carried by the insulated housing 35 which seats the contacts 36, 37. The inner end of plunger 40 extends adjacent the end of the shaft 32 of the valve 28 and slidably incloses an off-center projection 41 thereon. A spring-pressed ball detent 42 cooperates with spaced seats 43, 43 and functions to retain releasably the slide 40 in either an inner or outer position, as clearly shown in Figures 7 and 8. With the slide or actuator 40 in the inner position, or that shown in dotted lines in the figures, the offset end of the shaft 32 has been rotated counter-clockwise and the valve 28 has been moved to its upper position. The two valves 25 and 28 are connected as in the first embodiment. It follows that the valve 25 is positioned in the inlet-closing position. With the plunger 75

5 moved to its rearward position, that shown in full lines in Figures 7 and 8, the valve 28 has been pivoted to its passageway-closing position and the inlet 6 is closed and the dusting tools
10 are directly connected to the inlet of the fan chamber. Contacts 36 and 37 have again been closed and the motor circuit again includes the resistance R, a shoulder member 44 carried by the actuator 46 having contacted and moved the
15 movable contact 37.

I claim:

1. In a suction cleaner, suction-producing means, means to vary the suction produced by said suction-producing means, an air inlet, a second air inlet, means to connect selectively said inlets to said suction-producing means, and a single means to actuate said suction-varying means and said connecting means in a predetermined relationship.
2. In a suction cleaner, suction-producing means, means to vary the suction produced by said suction-producing means, a floor nozzle, a dusting tool conduit, means to connect selectively said nozzle or said conduit to said suction-producing means, means interconnecting said connecting means and said suction-varying means for synchronous adjustment, and means to operate said connecting means and said suction-varying means.
3. In a suction cleaner, suction-producing means including a motor having a plurality of circuits for multi-speed operation, a nozzle, a dusting tool conduit, means to connect selectively said nozzle or said conduit to said suction-producing means, and means to close automatically certain of said motor circuits to cause said motor to rotate at high speed upon the connection of said conduit to said suction-producing means.
4. The construction recited in claim 3 characterized in that the last mentioned means alter the electrical circuit of said cleaner motor upon connection of said nozzle to said suction-producing means.
5. In a suction cleaner, suction-producing means, means to vary the suction produced by said suction-producing means, an air inlet, a second air inlet, means to connect selectively said inlets to said suction-producing means, and means to actuate said suction-varying means and said connecting means, characterized in that said actuating means are manually operable and in that said connecting means and said suction-varying means are connected for movement in a definite relationship.
6. In a suction cleaner, suction-producing means, means to vary the suction produced by said suction-producing means, an air inlet, a second air inlet adapted to receive a dusting tool unit, means to connect selectively said inlets to said suction-producing means, and means opera-

ble by the connection of a dusting tool unit to said second inlet to operate said suction-varying and said connecting means to connect said suction-producing means to said second air inlet.

7. In a suction cleaner, a suction-creating fan, a multi-speed driving motor for said fan, an air inlet, a second air inlet, means to connect selectively said inlets to said fan, and means operating with said last mentioned means to cause said motor to rotate at one speed when said fan is connected to said first air inlet and at a higher speed when said fan is connected to said second inlet.

8. A suction cleaner of the on-the-floor cleaning type including a body adapted to receive a dusting tool unit for off-the-floor cleaning, suction-creating means including a motor having a plurality of circuits, a dusting tool unit adapted to be connected to said body, and cooperating means on said unit and on said body to alter said motor circuit to vary the motor speed upon the alteration of said cleaner for off-the-floor cleaning.

9. In a suction cleaner adapted for on-the-floor cleaning and for off-the-floor cleaning, suction-producing means, means to convert said cleaner from an on-the-floor unit to an off-the-floor unit, means to vary the suction produced by said suction-producing means, and single manually operable means to control said two last-mentioned means.

10. The construction recited in claim 9 characterized in that said manually operable means comprises a movable lever connected to said means to convert said cleaner.

11. In a suction cleaner adapted for on-the-floor cleaning and for off-the-floor cleaning, suction-producing means including a motor having relatively high and low speed circuits, a nozzle connected to said suction-producing means, a dusting tool inlet connected to said suction-producing means, valve means to open and close selectively said nozzle and said inlet to said suction-producing means, a switch controlling said circuits, and means interconnecting said switch and said valve means to effect actuation of the former upon adjustment of the latter.

12. In a suction cleaner, the combination of suction producing means including a motor having relatively high and low speed circuits, a nozzle normally communicating with said suction producing means for on-the-floor cleaning, a dusting tool unit adapted to be attached to said cleaner and connected with said suction producing means for off-the-floor cleaning, and a switch controlling said motor circuits and operative in response to the conversion of said cleaner to and from off-the-floor cleaning to vary the motor speed.

UNCAS A. WHITAKER. 60
